UNITED STATES PATENT OFFICE.

NICHOLAS HARRIS AND JOSEPH BRAY, OF RUSSELL GULCH, COLORADO.

BLASTING-FUSE.

SPECIFICATION forming part of Letters Patent No. 694,271, dated February 25, 1902.

Application filed November 29, 1901. Serial No. 84,042. (No model.)

To all whom it may concern:

Be it known that we, NICHOLAS HARRIS and JOSEPH BRAY, citizens of the United States, and residents of Russell Gulch, in the county 5 of Gilpin and State of Colorado, have invented a new and Improved Fuse, of which the following is a full, clear, and exact description.

Our invention relates to fuses, more particularly to the type used in blasting; and it 10 consists in providing the main longitudinal member of the fuse with a number of ancillary members for lighting the same, said ancillary members being preferably of tapering form for the purpose of enabling them to 15 be readily folded against or bent around the body of the main longitudinal member and being also spaced apart at definite intervals.

The invention consists in the novel construction and combination of the several 20 parts, as will be hereinafter fully set forth, and pointed out in the claims.

Reference is to be had to the accompanying drawings, forming a part of this specification, in which similar characters of reference indicate 25 corresponding parts in all the figures.

Figure 1 is an elevation showing the fuse ready for blasting and with the ancillary members folded; and Fig. 2 is an elevation, partly 30 in section, showing the ancillary members as unfolded.

The fuse is provided with a central combustible core 1, provided with a jacket 2 in the usual manner. From the central core 1 there are a number of ancillary branching 35 combustible members 3, provided with jackets 4 and terminating in points 5, which points are used in igniting the fuse. The cap 6, provided with the detonating mixture 7, is of the usual form. The object of the ancillary members is to enable the fuse to be readily ignited 40 without danger to the operative. By having these ancillary members spaced asunder at regular intervals any desired length of fuse can be placed between the ignition-point and 45 the detonating cap. For instance, the ancillary members may be placed at intervals of six, twelve, or eighteen inches, as desired.

The fuse is preferably manufactured as a continuous cord which can be wrapped upon 50 spools or in balls, the ancillary members being wound spirally around the cord, as shown in Fig. 1, so as to be out of the way as much

as possible. In this form the fuse is placed in the drill-hole ready for blasting, the cap being first applied in the usual manner. After 55 the fuse is in position any one or more of the ancillary members may be unfolded, as shown in Fig. 2. The presence of the ancillary members folded against the body of the longitudinal member is not at all objectionable and 60 does not impair the efficiency of the fuse in any manner or offer any inconvenience whatever.

One great advantage of our device is that all parts of the fuse are practically integral 65 and the miner has no two or more parts to assemble. He simply carries his spool or ball or piece of fuse, as the case may be, as he would any other similar article. He has nothing to tie, nothing to splice, nothing to 70 join together, and deals altogether with a very simple device, consisting practically of but one member.

Having thus described our invention, we claim as new and desire to secure by Letters 75 Patent—

1. A fuse, comprising a longitudinal combustible member, and a series of igniters extending laterally from the longitudinal member, and spaced at intervals thereon. 80

2. A fuse, comprising a continuous combustible member, and a series of ancillary combustible members for igniting said continuous member, said ancillary members extending laterally from the continuous member 85 and being foldable relatively thereto.

3. A fuse, comprising a continuous combustible member, and a series of ancillary combustible members extending laterally from said continuous member, each ancillary 90 member being provided at its free end with an ignitable tip.

4. A fuse, comprising a continuous combustible member, and a series of laterally-extending ancillary members, the said ancillary members being spaced along the length of the continuous member and ignitable independently of each other. 95

5. A fuse, comprising a main combustible member, and a series of laterally-extending ancillary members for igniting said combustible member, the said ancillary members being foldable around the main member. 100

6. As an article of manufacture, a cord-

like combustible member adapted to be cut into arbitrary lengths and provided with ancillary combustible members for igniting the same, the said ancillary members being of 5 tapering form for the purpose of enabling the same to be readily folded against said cord-like member without breaking, said ancillary members being disposed at definite intervals on said cord-like member.

In testimony whereof we have signed our names to this specification in the presence of two subscribing witnesses.

NICHOLAS HARRIS.
JOSEPH BRAY.
